ROAD MACHINE

Original application filed July 18, 1924, Serial No. 726,662, now Patent No. 1,660,050, dated February 21, 1928. Divided and this application filed February 4, 1928. Serial No. 252,013.

This invention relates to road working machinery, and the primary object is to provide a combination tractor-grader machine, with which is operatively associated a container for surfacing material that is so arranged with respect to the grader element and is provided with a feed or delivery mechanism that is connected with the engine of the tractor in such a manner that surfacing material such as sand, crushed rock, etc., may be applied to the road, under regulated power feed, either in advance of or at the rear of the grader element, selectively, as the machine advances over the road or highway. Further and more specific objects will be disclosed in the course of the following specification, reference being had to the accompanying drawing, wherein:

Fig. 1 is a side elevation of the machine, the near traction wheel and various other parts being broken away for purpose of illustration.

Fig. 2 is a sectional elevation as seen substantially on the line 2—2 in Fig. 1.

Fig. 3 is an elevation of the front end of the machine.

Fig. 4 is a fractional detail view as seen substantially on the line 4—4 in Fig. 2.

This application is a division of application Ser. No. 726,662, filed July 18, 1924, for road grader, resulting in Patent No. 1,660,050, issuing February 21, 1928.

Referring to the drawing more particularly, and by reference characters, A designates a tractor unit of the Fordson type, to which is secured and from which rearwardly extends an auxiliary frame B, a yoke C at the front end of the frame serving as a substitute for the usual or normal fore-carriage or steering truck of the tractor, which has been removed from the front end of the tractor. The construction of the frame B, its application to the tractor A, and other features, together with the method of and mechanisms for operating the machine which is thus formed, is illustrated and described in detail in the parent application above mentioned, and also in copending application, Ser. No. 717,511, filed June 3, 1924.

The steering truck and its steering mechanism may be briefly described as follows: The numeral 5 designates a yoke or frame, in the arms of which are journaled the ends of a shaft 6, which carries a drum 7 serving as a roller to roll down the road bed that has been traversed by a grader blade 8. The yoke 5 is pivotally secured, for transverse tilting movement, by a pivot 9, to a casting 10, which is journaled to rotate on a vertical center from the frame B, and which is provided with a worm gear 11 adapted to be actuated or rotated by a worm 12 on a transversely disposed shaft 13. This shaft is operated by a steering column 14, having a hand wheel 15, through a pair of bevel pinions which are not shown but are illustrated in the parent application, Ser. No. 726,662. The hand wheel 15 is arranged within convenient reach of an operator when seated in a seat 16 at the rear end of the machine, so that the operator at this point may steer the machine while having all its parts within convenient visual observation.

It may here be noted that the machine is provided with a duplicate set of controls, so that the entire machine may be controlled either from the rear seat 16 or from the normal tractor seat 17. In the steering device just described, steering may also be affected from the front or tractor seat by means of an endless cable 18 that passes over a sheave 19 on the post 14 and a sheave 20 on the tractor steering post 21 having the hand wheel 22, said cable first passing over a laterally disposed idle pulley, as disclosed in Patent No. 1,660,050, Fig. 2.

The usual clutch lever 23 and the gear shifting lever 24 of the tractor may also be controlled from the rear seat 16 by extension devices, which may be described as follows: The clutch lever 23, which is pivoted as at 25, is depressed by the foot of the operator (sitting in the seat 17) before the speed lever 24 can be shifted. It is connected by a cable 26 to an arm 27 on the right hand end of a transverse shaft 28 journaled in the frame B. At its left end this shaft is provided with a pedal lever 29, within leg reach of an operator in the seat 16.

The lever 24 is also controlled from the rear seat by a slidably journaled shaft 30 having a hand lever 31 at its rear end for turning and sliding the shaft. The front 5 end of this shaft 30 has a finger 32 that universally engages a bracket 33, on the lever 24; so that by operating the hand lever 31, the lever 24 may be shifted transversely, and back and forth, to effect the desired gear 10 shift.

The construction and operation of the grading unit proper may be briefly described as follows: The grader or scraping blade 8 is secured by suitable brackets 34 to a circle 35 15 adjustably secured, for rotation about a vertical pivot to a frame 36. This frame is pivotally secured, as by a loose pivot bolt 37 to the draw bar 38 of the tractor. At its rear end the frame 36 is provided with a 20 transverse beam 39 the ends of which are carried by suspension links 40 from arms 41 at the rear ends of shafts 42. The front ends of the shafts 42 are provided with worm pinions 43 which mesh with worms 44 of 25 laterally disposed hand wheels 45. Thus either or both ends of grader blade 8 may be manually raised or lowered, as desired, by operating the hand wheels 45.

Secured upon the rear part of the frame 30 B is a large box or container 46 in which is placed the sand, crushed rock or road treating or surfacing material to be used. The end walls of the box are provided at their lower ends with wide slots 47, through which, 35 and over the floor 48 of the container, travels an endless conveyor belt 49. This belt operates over an idle shaft 50 in the rear of the frame B, and over a drive shaft 51 that is journaled in the frame in advance of the 40 box 46. When the conveyor 49 is idle no appreciable amount of material will escape through the slots 47, as such material will have a tendency to choke up in the slots, and on the conveyor ends, but as soon as the conveyor 45 is actuated, either forwardly or rearwardly it will feed the material out, at one end or the other of the box, whereupon it will fall upon the road bed either in advance or in the rear of the grading blade and roller.

50 The shaft 51 is provided, at its right end, with a friction disk 52 with which is associated a driving friction roller 53. The roller 53 is slidably keyed on a longitudinally extending shaft 54 that is journaled to the 55 frame B, at one side, and is provided at its forward end with a bevel pinion 55 that meshes with a similar pinion 56 at the upper end of a shaft 57. The shaft 57 rotates in suitable bearings 58, and at its lower end is 60 driven by the usual power shaft 59 of the tractor through suitable bevel pinions 60. The friction roller 53 is in constant frictional contact with the disk 52, but is radially adjustable with respect thereto, such adjustment being effected by means of a fork 61 on 65

a rod 62. This rod 62 is slidable in bearings 63, and, at its front end connects with a shift lever 64, whereby it may be manually operated from the front seat 17. It may also be shifted, from the rear seat 16, through a 70 hand lever 65, a shaft 66, and an operating finger 67 that engages between two lugs 68 on the rear end of the rod 62.

The shaft 54 is continuously driven from the engine, but the conveyor 49 may be rendered idle by shifting the friction roller 53 to a position in alignment with the shaft 51 where it will have no driving effect on the disk 52. When it is now desired to feed material from the box 46 and drop it down in front of the grader blade the roller 53 is gradually moved forwardly whereupon it drives the disk and the upper run of the conveyor starts to feed forwardly. And, conversely, when it is desired to feed the material rearwardly, the hand lever 64, or 65, is moved rearwardly with a corresponding reversal of the conveyor drive, as the roller 53 will then engage the disk 52 rearward of its center.

It will thus be seen that a normal tractor converted to the attachment described comprises a single unit machine in which both the tractor and the road treating apparatus is within the complete control of a single operator or in which some of the controls may be manipulated by one operator while the remaining controls may be handled by a second operator and that the machine thus formed having a comparatively short wheel base and virtually only a three wheel support contact with the road is capable of quickly responsive steering control by either or both of the operators. The essential advantage and function of the machine as far as the herein claimed invention is concerned, however, is the fact that it incorporates, with a road grading tool, means for supplying material to the road surface either in advance or in the rear of the tool, selectively, as circumstances may require, and that such material supplying means may be power actuated so that it may be quickly set in motion in either direction, at the slightest effort of the operator, who is watching the road condition, both in advance and immediately in back of the blade as the machine is travelling over the road. This is a most vital and valuable consideration, in a machine of this character, because it is often desirable in the proper treatment of a road, to provide surfacing or treating material in advance of the blade in some instances, while back of it in other instances, depending upon various road conditions and planing or cutting depth of the grader blade.

The structure, object, and function of the invention thus having been described, what is claimed is:

1. The combination with a vehicle having a power element for propelling the same, of a container on the vehicle, a road working tool mounted for operation under the vehicle, and means adapted to be driven by said power element for discharging material from the container whereby it may be dropped upon the road in advance of or rearwardly of the tool, selectively.
2. The combination with a vehicle, of an implement arranged thereunder to be drawn therewith, a container arranged on the vehicle, and means for delivering material in the container to either end thereof so that such material may be selectively dropped either in front or rearwardly of the implement.
3. The combination with a vehicle, of a road grader adjustably secured under the vehicle, a container arranged on the vehicle, and a power operated mechanism for delivering material from either end of the container, selectively.
4. A combination tractor-grader, comprising a power vehicle having an operator's station thereon, a grader blade arranged under the vehicle, a container carried on the vehicle, over the grader-blade, means for delivering material from either end of the container whereby such material may be selectively dropped upon the road either in advance or rearwardly of the grader blade.
5. A combination tractor-grader, comprising a power vehicle having an operator's station thereon, a grader blade arranged under the vehicle, a container carried on the vehicle over the grader-blade, means for delivering material from either end of the container whereby such material may be selectively dropped upon the road either in advance or rearwardly of the grader blade, and controls extending to within reach of the operator at said station, for controlling said delivery means and for adjusting the grader blade.

45 In testimony whereof we affix our signatures at Minneapolis, Minnesota, this 28th day of January, 1928.

ADOLPH RONNING.
